KILN APPARATUS

John J. Schmidt, Frederick, Md., assignor to
 The Frederick Iron & Steel Company,
 Frederick, Md., a corporation of Maryland

Application July 26, 1930. Serial No. 470,975

9 Claims. (Cl. 110—28)

My invention relates broadly to methods of firing brick or other ceramic material and more particularly to an automatic firing method of burning brick or other ceramic material.

8 One of the objects of my invention is to provide a method for automatically firing groups of chambers in a kiln.

Another object of my invention is to provide a system for automatically and progressively firing groups of chambers in a continuous kiln.

10 Still another object of my invention is to provide automatic means for progressively and automatically firing groups of chambers in a continuous kiln while adjacent groups of chambers 15 are permitted to cool in preparation for refiring, the supply of fuel being regulated automatically.

15 A further object of my invention is to provide means for attachment to a continuous kiln for automatically feeding fuel to the several combustion chambers of a continuous kiln and establishing a predetermined undraft and side-draft for the burning of fuel in suspension for firing selected groups of chambers in the continuous kiln.

20 A still further object of my invention is to provide a method and apparatus for firing kilns for rendering the operation of such kilns less expensive than has heretofore been possible with methods of hand firing.

25 Another object of my invention is to provide automatic fuel feeding means for kilns by which coal may be burned in suspension and thereby decrease the cost of fuel consumption in kilns.

Still another object of my invention is to provide 30 an arrangement of updraft tuyère for kilns adapted to cooperate with a forced draft established in selected combustion chambers of the kiln for the burning of fuel in suspension and automatically firing groups of chambers in the 35 kiln.

Other and further objects of my invention reside in the construction of automatic fuel feeding mechanism for continuous kilns and in the method of firing the kiln as set forth more fully 40 in the specification hereinafter following by reference to the accompanying drawings, in which:

Figure 1 is an elevational view of a portion of a continuous kiln and fuel feeding devices embodying the principles of my invention; Fig. 2 45 is a view of the kiln and fuel feeding devices taken along the line 2—2 of Fig. 1; Fig. 3 is an enlarged fragmentary cross-sectional view taken on line 3—3 of Figs. 1 and 4; Fig. 4 is an enlarged elevational view partially broken away 50 and illustrated in cross-section showing one of

the combustion chambers in the continuous kiln and showing the arrangement of fuel feeding mechanism with respect thereto; Fig. 5 is an elevational view of the combustion chamber shown in Fig. 4 but illustrating the fuel feeding mechanism raised from fuel feeding position over the combustion chamber preparatory to transfer to another combustion chamber along the continuous kiln; Fig. 6 is a plan view of the fuel feeding mechanism in position over one of the combustion chambers, parts of the mechanism being broken away to illustrate adjacent parts thereof; Fig. 7 is a plan view of one form of removable tuyère which may be used in each combustion chamber for creating forced draft; Fig. 8 is a view of a modified form of the removable tuyère partially broken away and shown in cross-section; Fig. 9 is a view partially broken away and shown in cross-section of a further modified form of removable tuyère which may be installed in each of the combustion chambers of the kiln in accordance with the principles of my invention; Fig. 10 is a fragmentary view illustrating a modified construction of apparatus for creating an updraft through tuyère boxes in 60 groups of the combustion chambers of the continuous kiln; Fig. 11 is a fragmentary cross-sectional view through the kiln showing a modified arrangement of the fuel feeding mechanism; Fig. 12 is a plan view of the fuel feeding mechanism shown in Fig. 11 with parts shown in section; Fig. 13 is a fragmentary view on line 13—13 of Fig. 14 showing the arrangement of forced draft control valves for the fuel feeding mechanism of Figs. 11 and 12; Fig. 14 is a fragmentary cross-sectional view on line 14—14 of Fig. 13; and Fig. 15 is a cross-sectional view on line 15—15 of Fig. 14.

For the purpose of explaining the principles of my invention the continuous kiln has been shown 95 arranged for the automatic firing of brick. While I have illustrated the fuel feeding mechanism of my invention particularly adapted for the firing of groups of combustion chambers in a continuous brick kiln, I desire that it be understood that the 100 principles of my invention may be applied to kilns employed for firing other ceramic materials.

Heretofore in the art the human element has been depended upon for supplying fuel from time to time to the combustion chambers of the continuous kiln. It has been necessary to hand fire the combustion chambers and to hand fire the chambers from firing holes disposed lengthwise and crosswise in the kiln. Heretofore the combustion chambers built in the doorways of the 110

firing furnace have employed no grates, the fire being built on the floor of the doorway. When the kiln compartment has been filled with bricks to be fired the doorway to the combustion chamber 5 is built up and closed by masonry. After the firing of the bricks has been completed this doorway is again opened and through it the bricks which have been heat treated are removed. The hand firing is accomplished through a small door 10 in the doorway. The operator sights through a small opening in the doorway to the combustion chamber in an effort to learn the condition of the fire and then shovels in charges of coal to maintain the fire within the combustion chamber. 15 Prior methods require that lump coal be used. This lump coal is relatively expensive and it has been one of the objects of my invention to provide a method of burning coal and slack in the kiln which may be obtained as waste from lump coal. 20 The loss of heat which is occasioned in the old methods of firing a continuous kiln is one of the great disadvantages of the manually fired kiln. Heretofore, each time the door of the combustion chamber has been opened it has resulted in a 25 cooling of the kiln resulting in incomplete combustion and a lowering of the temperature in the immediate vicinity of the combustion chamber. This results in the lowering of temperature throughout the entire area of the kiln. Obviously the subsequent charges to the combustion chambers with the accompanying cooling of the furnace chamber whenever the chamber is charged, require a larger amount of fuel to compensate for temperature losses and incomplete 30 combustion. A considerable saving in fuel combustion is obtained in the system of my invention by the burning of inexpensive coal and slack in suspension in a manner where it is unnecessary to expose the combustion chamber to the opening and closing of a fuel feeding door with the accompanying inrush of cold air. Furthermore the combustion becomes much more uniform as the coal is slowly and continuously, or in some instances intermittently, fed into the hot fire within 35 the combustion chamber by automatic means. The volatile matter in the coal is driven off either partially or completely and then the partially burned coal dropped to a fuel bed which is supplied with forced draft and combustion completed. 40 As the fuel is burned in suspension a hot gas is produced which circulates around the brick in the kiln subjecting the brick to the required firing action. 45

In a continuous kiln groups of combustion chambers are fired simultaneously. I provide automatic fuel feeding mechanism adapted to automatically inject coal adjacent the side of the combustion chamber under pressure. Simultaneously air is introduced under pressure adjacent the 50 base of the combustion chamber and the fuel burned in suspension between the points of introduction thereof and the several combustion chambers.

The fuel feeding mechanism and air injecting tuyères are adapted to be shifted in position from one group of combustion chambers to an adjacent group of combustion chambers along the continuous kiln. Several groups of combustion chambers may be fired simultaneously at spaced 55 intervals along the kiln. Provision is made for raising the automatic fuel feeding mechanism out of connection with combustion chambers in which firing has been completed and moving the fuel feeding mechanism to other groups of combustion chambers for again starting a firing proc-

ess. I may embody the fuel feeding mechanism in a number of different designs and may inject the fuel into the combustion chambers from different positions. The several embodiments of my invention which have been illustrated are intended 60 to set forth the method of effecting combustion within the combustion chambers of the kiln and specific details of the firing mechanism may be modified in carrying out the objects of my invention. The several embodiments are therefore intended 65 to be considered as setting forth the theory and method of operation of the firing operation of my invention rather than limiting the particular manner in which the invention may be carried out. 70

Referring to the drawings in detail, reference characters 1, 2, 3, 4, 5, 6, 7, 8 represent combustion chambers along one side of a continuous kiln. Reference characters 9, 10, 11, 12, 13, 14, 15 and 16 represent combustion chambers along the opposite side of the continuous kiln. Rails 17 and 18 are positioned along the top of the kiln along which the fuel cars 19 and 20 move. The kiln is shown having a roof 22 extending thereover and supported by suitable columns indicated at 21. An I beam 23 is suspended from the roof structure 22 over the combustion chambers for effecting a transfer or shift of the fuel feeding mechanism from one position to another along the combustion chambers. The fuel feeding mechanism comprises a fuel receiving hopper and a conveyor 105 for advancing the fuel into the combustion chambers. Groups of four combustion chambers can be automatically fired simultaneously in the system of my invention. As represented in Fig. 1, the fuel feeding hoppers are designated at 24, 110 25, 26 and 27 on one side of the kiln located over combustion chambers 1, 2, 3 and 4, respectively. At the opposite side of the kiln fuel feeding hoppers 36, 37, 38 and 39 are provided over combustion chambers 16, 15, 14 and 13 respectively. 115 Each fuel feeding apparatus includes a driving motor and a fan blower for creating a draft for forcing coal into the combustion chamber from an elevated position. A fuel conveying conduit 24c extends beneath hopper 24 in which the screw 120 conveyor 49 is operated by gear connection with driving motor 46. The conduit 24c terminates in a downwardly directed hood 48 closed by cover 48a. A fan 47 driven by geared connection with motor 46 creates a draft tending to support combustion of the particles of coal which are fed from the hopper 24 to the position indicated at 125 65 in Fig. 3. The gases created by the combustion in the combustion chambers are directed against the brick 53 located interiorly of the kiln within the chamber 45 subjecting the brick to firing action. Each combustion chamber is provided with a port 50 with which the hood 48 is adapted to register during the firing process. The block and tackle 24a is utilized for the purpose of shifting the hopper from one combustion chamber to another along the kiln. As illustrated in Figs. 3 and 4 the fuel feeding mechanism has been lowered into position with respect to the aperture 50 of the combustion chamber. 130

In Fig. 5, the fuel feeding mechanism has been raised from connection with the combustion chamber 1, which action simultaneously disconnects the conduit 55 from the riser 28 at the annular connection 54. The damper 66 is disposed in the conduit 55 for controlling the velocity of flow of the air which is forced through riser 28 into the conduit 28a leading to the tuyère box 52. Conduits and risers which are connected by joints 28b are provided adjacent each set of com- 135 140 145 150

bustion chambers as shown in Figs. 1 and 2 at 28, 29, 30, 31, 32, 33, 34, 35, 40, 41, 42, 43, 67, 68, 69 and 70. It is therefore only necessary to release the conduit 55 from the upper end of the riser 28 5 when transferring a hopper from one combustion chamber to another.

The connection with the upper end of the riser 28 is automatically established when the elbow 54 of conduit 55 is lowered into position as shown 10 in Figs. 3 and 4. The hoppers are each provided with a chute as has been represented at 24b, 25b, 26b and 27b for directing the coal from the charging car into the several hoppers.

In Fig. 8 I have shown a modified form of 15 tuyère box indicated at 56 where a conical plate 57 is provided for the banking of the fuel within the combustion chamber. As illustrated in Fig. 9, the tuyère box may be constructed of greater depth as shown at 58, with the fuel plate 20 59 disposed in a conical position directed downwardly, apertures being provided in the plate 59 for the passage of forced draft through the plate.

Instead of obtaining the draft for the tuyère boxes from the individual fans on the fuel feeders, I may provide a central fan 61 as shown in 25 Fig. 10 and supply forced draft through conduit 60 to each of the combustion chambers by means of risers 63 leading to tuyère boxes represented at 62 and each having inlet ports 62a 30 in the bottom thereof. In this instance draft is regulated by dampers 64 mounted in the risers 63.

In Figs. 11-15, I have illustrated the modified form of fuel feeding mechanism. In this arrangement the fuel hopper 24 is supported by block and tackle 24a and may be rocked laterally to align and engage fuel feeding tube 24c with the aperture leading to the combustion chamber and align and engage the ends of conduit 55 through coupling 55a, the fuel hopper being thereafter allowed to rest upon a movable platform 71 operative on rail 72, extending around the continuous kiln. An aperture is provided through the front wall of each combustion 40 chamber, which aperture is lined with fire brick as indicated at 73. The fuel delivery portion 24c of the stoker projects through collar 77 to a position within the wall of the combustion chamber in alignment with the tuyère box 75. 45 Tuyère box 75 is shaped to conform with the interior walls of the aperture through the combustion chamber and conforms with the fire brick lining 73. The upper surface of the tuyère box is apertured as represented at 74 for the passage of forced draft delivered through pipe line 76 from tap 79 in the air conduit 55. Conduit 55 connects with the riser 28 which connects through angle 28a with the lower tuyère box 52 as hereinbefore described. A connection 55a may be made between the forced draft mechanism and the riser at each of the combustion chambers. A valve 78 is positioned in the air line 76 whereby flow of air into the tuyère box may be controlled. The spiral conveyor 49 advances the coal delivered from hopper 24 to a position on plate 74 of tuyère box 75 where the fuel is heated by the combustion at 65 within the combustion chamber. The volatile gases are driven off thereby serving to assist in sustaining combustion within the combustion chamber. The forced draft for both the tuyère box 75 and the tuyère box 52 is supplied from the common means which drives the spiral conveyor 49 for the coal. The amount of draft may

valves 66 and 78 in selective degrees. The chute 24b on hopper 24 registers at each combustion chamber with an extension chute 30 through which charges of coal are directed from the car 19 at the top of the kiln. The process set forth in Figs. 11-15 differs from the process hereinbefore described in that the period of stoking or volatilizing of the coal is prolonged thereby increasing the efficiency of operation of the firing process by securing increases in temperature and more complete combustion without excessive use of fuel.

Throughout all forms of the process of my invention, I employ cheap coal burned in suspension as distinguished from lump fuel which 90 can be more advantageously used in other fields.

Throughout the specification and drawings I have particularly described my invention as applied to continuous kilns but it will be understood that I may employ the principles of my 95 invention in connection with rectangular kilns, circular kilns, tunnel kilns, or other types of kilns used for various purposes.

While I have described my invention in certain preferred embodiments and for a particular 100 form of kiln, I desire that it be understood that modifications may be made and that no limitations upon my invention are intended other than are imposed by the scope of the appended claims.

What I claim as new and desire to secure by 105 Letters Patent of the United States is as follows:

1. In combination with a kiln having a plurality of combustion chambers, a plurality of groups of automatic firing means for cooperating with 110 selected groups of combustion chambers, each combustion chamber having fuel and air intake connections and each firing means having fuel and air discharge connections for detachable connection with the intake connections of the combustion chambers, and means for progressively shifting the groups of firing means along the kiln from one group of combustion chambers to another.

2. In combination with a kiln having a plurality 115 of combustion chambers each formed with an upper fuel inlet and having a tuyère box near its bottom provided with an air inlet, a plurality of groups of automatic firing means for cooperation with selected groups of combustion chambers 120 each having a fuel hopper provided with a discharge adapted to be releasably connected with the fuel inlet of a combustion chamber and a fan having a housing provided with a discharge 125 adapted to be releasably connected with the air inlet of the tuyère box of the combustion chamber, and means for raising the groups of firing means to separate the air and fuel discharges thereof from the air and fuel inlets of the combustion chambers and shift the groups of firing 130 means along the kiln from one group of combustion chambers to another.

3. In combination with a kiln having a plurality 135 of combustion chambers each formed with an upper fuel inlet and having a tuyère box near its bottom provided with an air inlet, a plurality of groups of automatic firing means for cooperation with selected groups of combustion chambers each having a fuel hopper provided with a discharge 140 adapted to be releasably connected with the fuel inlet of a combustion chamber and a fan having a housing provided with a discharge 145 adapted to be releasably connected with the air inlet of the tuyère box of the combustion chamber, a conveyor for moving coal through the dis- 150

75 be accurately regulated by manual control of

- charge of said hopper, common means for actuating the fan and conveyor to cause coal and air to be fed simultaneously through the fuel inlet and tuyère box into the combustion chamber in proportional relation to each other, and means for raising the groups of firing means to separate the air and fuel discharges thereof from the fuel and air inlets of the combustion chambers and shift the groups of firing means from one group 10 of combustion chambers to another. 4. In combination with a kiln having a plurality of combustion chambers each formed with an upper fuel inlet and having a tuyère box near its bottom provided with an air inlet, a plurality of 15 groups of automatic firing means for cooperation with selected groups of combustion chambers each having a fuel hopper provided with a discharge adapted to be releasably connected with the fuel inlet of a combustion chamber and a fan 20 having a housing provided with a discharge adapted to be releasably connected with the air inlet of the tuyère box of the combustion chamber, an air inlet being provided for admitting air to the fuel inlet to drive gases from coal into the 25 combustion chamber, and means for elevating the groups of firing means to separate the air and fuel discharges thereof from the air and fuel inlets of the combustion chambers and shift the groups of firing means along the kiln from 30 one group of combustion chambers to another. 5. In combination with a kiln having a plurality of combustion chambers each formed with an upper fuel inlet and having a tuyère box near its bottom provided with an air inlet, a plurality of 35 groups of automatic firing means for cooperation with selected groups of combustion chambers each having a fuel hopper provided with a discharge adapted to be releasably connected with the fuel inlet of a combustion chamber and a fan 40 having a housing provided with a discharge adapted to be releasably connected with the air inlet of the tuyère box of the combustion chamber, tracks extending longitudinally of the kiln above the combustion chambers, and hoisting means 45 engaged with said hoppers and movable along said tracks for elevating the hoppers and separating the air and fuel inlets whereby the groups of firing means may be shifted along the tracks from one group of combustion chambers to another. 50 6. In combination with a kiln having a plurality of combustion chambers each formed with an upper fuel inlet and having a tuyère box near its bottom provided with an air inlet, a plurality of groups of automatic firing means for cooperation with selected groups of combustion chambers each having a fuel hopper provided with a discharge adapted to be releasably connected with the fuel inlet of a combustion chamber and a fan 55 having a housing provided with a discharge adapted to be releasably connected with the air inlet of the tuyère box of the combustion chamber, tracks extending longitudinally of the kiln above the combustion chamber, and hoisting means 60 engaged with said hoppers and movable along said tracks for elevating the hoppers and separating the air and fuel inlets whereby the groups of firing means may be shifted along the tracks from one group of combustion chambers to another. 65 of the kiln above the combustion chambers, and hoisting means engaged with said hoppers and movable along said tracks for elevating the hoppers and separating the air and fuel inlets whereby the groups of firing means may be shifted along the tracks from one group of combustion chambers to another. 7. In combination with a kiln having a plurality of combustion chambers, a portable firing and air blast mechanism comprising a fuel hopper adapted to be shifted from one combustion chamber to another progressively along the kiln, a tuyère box inserted adjacent the bottom of each combustion chamber, an air conduit extending from said tuyère box, fuel feeding means leading from the fuel hopper and adapted to establish connection with the upper portion of said combustion chamber coincident with the connection of said air blast mechanism with said air conduit, and common means for actuating said fuel feeding means and establishing a forced draft through the tuyère box to support combustion within the combustion chamber. 8. In combination with a kiln having a plurality of combustion chambers, means for introducing fuel at a predetermined rate in a substantially horizontal direction adjacent the upper end of selected combustion chambers, means for establishing a forced draft adjacent the bottom of each combustion chamber, common means for actuating both of said means for feeding fuel and air to the combustion chambers at a rate whereby gases are driven from the fuel, means for shifting said means from one combustion chamber to another progressively along said kiln, a pipe connecting the air injecting means with the fuel introducing means, and means in said pipe for controlling the amount of air delivered to the point of fuel introduction. 9. In combination with a kiln having a plurality of combustion chambers each having a fuel inlet in its upper portion and a tuyère box near its bottom having an air inlet, a fuel hopper, a fan having a housing provided with an outlet, the fan housing and hopper being movable as a unit along the kiln from a position adjacent one combustion chamber to another and when in a set position having their outlets communicating with the fuel inlet of a combustion chamber and air inlet of the tuyère box thereof, and means for feeding fuel through the fuel inlet and air through the air inlet in such proportional relation to each other that a greater quantity of air is fed into the combustion chamber than required for combustion.

JOHN J. SCHMIDT,
